US00D601812S

(12) **United States Design Patent**
Bruun et al.

(10) **Patent No.:** **US D601,812 S**
(45) **Date of Patent:** **** Oct. 13, 2009**

(54) **ABSORBING PAD**

(75) Inventors: **Jonas Bruun**, Lund (SE); **Arne Lindqvist**, Sodertalje (SE); **Sammy Hallgren**, Malmo (SE)

(73) Assignee: **Paper-Pak Sweden AB**, Aneby (SE)

(**) Term: **14 Years**

(21) Appl. No.: **29/329,351**

(22) Filed: **Dec. 12, 2008**

Related U.S. Application Data

(62) Division of application No. 29/269,281, filed on Nov. 28, 2006, now Pat. No. Des. 586,128.
